HAND-OPERATED SEWING MACHINE

Nathan K. Morris, Neptune City, N.J. 07753

Filed Mar. 13, 1968, Ser. No. 10,949

Term of patent 7 years

Int. Cl. D15—09

U.S. Cl. D70—1

FIG. 1

FIG. 3

FIG. 2

FIG. 4

FIG. 5

FIG. 6

FIGURE 1 is a perspective view of a hand-operated sewing machine showing my new design, the broken line showing of a spool and thread being for purposes of illustration;

FIGURE 2 is a side elevational view thereof;
FIGURE 3 is an end view as seen from the left of FIGURE 2;

FIGURE 4 is a top plan view;

FIGURE 5 is a bottom plan view; and

FIGURE 6 is an end view as seen from the right of FIGURE 2.

I claim:

The ornamental design for a hand-operated sewing machine, as shown and described.
